(57) CLAIM

The ornamental design for a plant watering device with anti-flow stoppage tilt therefor, as shown and described.

DESCRIPTION

FIG. 1 is a perspective view of a plant watering device with anti-flow stoppage tilt therefor;

FIG. 2 is a top perspective view thereof;

FIG. 3 is a bottom elevational view thereof;

FIG. 4 is a rear elevational view thereof;

FIG. 5 is a side elevational view thereof;

FIG. 6 is a front elevational view thereof;

FIG. 7 is a cross-sectional view of FIG. 2 taken along line 1a—1a showing the anti-flow stoppage tilt in a resting condition;

FIG. 8 is the cross-sectional view in FIG. 7 showing the anti-flow stoppage tilt in a condition of use;

FIG. 9 is another top perspective view showing a modified alternate plan view showing my new design;

FIG. 10 is a bottom plan view of FIG. 9 thereof;

FIG. 11 is a rear plan view thereof;

FIG. 12 is a side plan view thereof; and,

FIG. 13 is a front plan view thereof.

The broken line shown in FIG. 1 is for illustrative purposes only and forms no part of the claimed design.

The opposing side view shown in FIGS. 5 and 12 are mirror images thereof.
